UNITED STATES PATENT OFFICE.

WILLIAM T. HENSLEY, OF CONNERSVILLE, INDIANA, ASSIGNOR, BY MESNE ASSIGNMENTS, TO BOUND BROOK ENGINE & MFG. CO., A CORPORATION OF DELAWARE.

SHEET-METAL FORM FOR ARMATURE-COILS.

1,238,911.

Specification of Letters Patent.

Patented Sept. 4, 1917.

Application filed May 11, 1912. Serial No. 696,608.

To all whom it may concern:

Be it known that I, WILLIAM T. HENSLEY, a citizen of the United States of America, and resident of Connersville, Fayette county, Indiana, have invented a certain new and useful Improvement in Sheet-Metal Forms for Armature-Coils, of which the following is a specification.

My invention relates to the manufacture 10 of armature coils of that particular kind in which the conductors are composed of flat strips of metal. Prior to my invention these had been made in various ways, including the use of strap metal, but the cost thereof 15 was greater than was necessary.

The object of my invention is, therefor, to provide a form for armature coils of such a character that these coils may be made from sheet metal, thus very materially reducing 20 the cost of manufacture thereof, and without rendering the same any the less satisfactory in use.

To the foregoing and other useful ends my invention consists in matters hereinafter set 25 forth and claimed.

In the accompanying drawings—

Figure 1 is a plan view of a sheet metal blank formed by shearing or otherwise cutting the same from the body of sheet metal. 30 Fig. 2 shows said blank in position to be drawn through the device by which the sharp corners are removed from the longitudinal edges thereof.

Fig. 3 shows the blank strip after being 35 subjected to the treatment by which the said sharp corners are removed.

Fig. 4 is a diagrammatic view illustrating the method of and means by which the sharp corners are stripped or eliminated from the 40 edges of the sheet metal blank.

Fig. 5 is a cross section on line 5—5 in Fig. 1.

Fig. 6 is a similar section on line 6—6 in Fig. 3.

Fig. 7 shows the blank in cross section, and the device for smoothing the edges in elevation, which illustrates the manner in which the edges of the blank are rounded. 45

Fig. 8 is a perspective of the finished 50 armature conductor.

As thus illustrated, the sheet metal blank A is made by shearing or cutting the same from a large sheet of metal, it being observed that the blank is composed of two

parallel portions *a* arranged with their 55 edges close together throughout the length thereof, except where the slot *a*¹ extends for a short distance from the union *a*² between the two parallel portions.

The blank when thus made is substantially 60 in the form of a flat strip of metal.

The device by which the sharp corners of the longitudinal edges of the blank are eliminated to round the edges of the blank may be of any suitable character. For example, as shown in Figs. 2, 4 and 7, the said device consists of a pair of blocks B, formed with corresponding grooves *b* which, when the two blocks are placed together, form parallel passages or openings. The two parallel 70 portions *a* of the blank are laid in the grooves or channels *b* of one of said blocks, in the manner shown in Fig. 2, whereby the small ridge or portion *b*¹ of said block enters the slots *a*¹, and the other block is then 75 placed in position, as shown in Fig. 7, and any suitable means are then employed for holding the two blocks together with the slotted portion of the blank between them. These channels or grooves in the blocks are 80 of the desired formation—that is to say, they are made with rounded sides, and when the blank is forcibly pulled between the two blocks the sharp corners of the edges thereof are eliminated, with the result that the longitudinal edges of the blank are made round 85 and smooth, as shown more clearly in Fig. 6; it being observed that in Fig. 5 the condition of said edges previous to this operation is also clearly illustrated. 90

Any suitable means can be employed for pulling the blank through the device for eliminating or smoothing the edges of the blank, such, for example, as the tongs C shown in Fig. 4, it being observed that 95 these have a toggle action which makes them capable of exerting a powerful grip on the end of the blank.

This operation serves also, it will be seen, to produce a separation of the two parallel 100 portions of the blank, as shown in Fig. 3. In other words, the operation produces a continuation of the slot *a*¹ to the end of the blank.

The flat conductor thus formed is now 105 ready for further treatment, in any suitable manner, to render it suitable for use in making the coil of an armature. For example,

it may be bent into the shape shown in Fig. 8, by bending the two parallel portions apart, which is necessary and desirable for some types of armature.

5 Thus it will be seen that by my invention I make it possible to produce a satisfactory armature conductor from sheet metal. Notwithstanding the sharp and objectionable edges which the blank has when first taken 10 from the body of sheet metal, the conductor is of entirely satisfactory form and character when finally completed and ready for use, as these sharp edges have become round and smooth and free from any characteristic 15 which might render them unsuitable for use in constructing an armature.

What I claim as my invention is:

1. As an article of manufacture, a sheet metal blank for making an armature coil, 20 said blank comprising a straight strip of sheet metal divided longitudinally midway between its edges except at one end thereof,

the division adjacent this end being wider and forming a slot.

2. As an article of manufacture, a sheet 25 metal blank for making an armature coil, said blank comprising a straight strip of sheet metal divided longitudinally midway between its edges except at one end thereof.

3. As an article of manufacture, a sheet 30 metal form for making an armature coil, said form comprising a straight strip of sheet metal divided longitudinally midway between its edges, except at one end thereof, 35 the division adjacent this end being wider and forming a slot, the divided portions being rounded on their edges.

Signed by me at Connersville, Indiana, this 7th day of May, 1912.

WILLIAM T. HENSLEY.
